UNITED STATES PATENT OFFICE.

JAMES M. DULANEY AND THOMAS OWENS, OF TOPEKA, KANSAS.

CAR-COUPLING.

SPECIFICATION forming part of Letters Patent No. 271,045, dated January 23, 1883.

Application filed June 30, 1882. (No model.)

To all whom it may concern:

Be it known that we, JAMES M. DULANEY and THOMAS OWENS, of Topeka, in the county of Shawnee and State of Kansas, have invented a new and Improved Car-Coupling, of which the following is a full, clear, and exact description.

The invention consists in the combination and arrangement of a draw-head and its accessories, hereinafter fully described and set forth.

Reference is to be had to the accompanying drawings, forming part of this specification, in which similar letters of reference indicate corresponding parts in all the figures.

Figure 1 is an end elevation of our improved car-coupling, parts being broken out and in section. Fig. 2 is a longitudinal sectional elevation of our improved car-coupling. Fig. 3 is a longitudinal elevation of the end parts of two cars provided with our improved car-coupling. Fig. 4 is a perspective view of partitions L inverted. Fig. 5 is a section on line x x, Fig. 3.

The draw-head A contains a longitudinally-movable buffer-block, B, having a projecting stem, B', at its end, which stem is surrounded by spiral spring B², resting against the rear end of the recess in the draw-head. A plate or tongue, C, is attached to the bottom of the buffer-block B, and projects from the front end of the same. A tube, D, projects downward from the front end of the bottom of the draw-head, and is provided with a longitudinal slot, d, in its rear side. This tube D contains a vertically-movable coupling-pin, E, which rests on a spiral spring, E', contained in the tube D. The tube D is braced by a rod, D', attached to the bottom of the draw-head and to the bottom of the tube D. The draw-head is provided at its front end, on the top and bottom, with suitable apertures for the coupling-pin E. A pin, a, attached to the lower end of the coupling-pin E, projects through the slot d of the tube D, and to this pin a the inner ends of the levers F, reaching to the sides of the car, are attached. These levers F are pivoted to the lower ends of link-pieces f, pivoted to the ends of a bar, G, attached to the front end of the bottom of the draw-head

parallel with the end of the car, the ends of which bar G are braced and supported by brace-rods g, running over the top of the draw-head and secured to the ends of the bar G.

Weights H are attached to loops H', passed around the levers F, and can be locked in any desired position on the levers by means of binding-screws h. A link-lifting lever, I, is pivoted to one end of the bar G in such a manner that its inner end can move up and down in front of the end of the draw-head. This inner end of the lever I is provided with two upwardly-projecting prongs or studs, i, which are separated such a distance that the link J can pass in between them. This lever I is guided by a longitudinal guide-loop, K, attached to the bar G. The lever I is also provided with an adjustable weight, H², in the same manner as the levers F. If desired, two levers I may be used, one reaching to each side of the car. The draw-head A is held between two longitudinal vertical partitions, L, projecting from the bottom of the car.

Eccentric rollers M are rigidly mounted on transverse shafts M' in the top and bottom of the partitions L, the distance between these rollers being equal to the height of the draw-head A. Crank-arms m are rigidly mounted on the ends of the shafts M', outside of one of the partitions L, and the ends of all four cranks m are pivoted to a plate, N, so that all four cranks m will operate together. A circular disk, O, provided near its periphery with a series of apertures, o, is mounted on one end of the upper forward shaft M', this shaft being extended to the side of the car and provided on its outer end with a crank-handle, P. A latch-pin, Q, has bearings in the side of the car and in a block, q, near the disk O, and can be moved to and from this disk, its inner end being adapted to be passed into the apertures o in disk O. A spring, Q', surrounds this latch-pin Q and presses it toward the disk O. A curved lever, n, passes through the outer end of the latch-pin Q, and is pivoted to the side of the car, which is provided with a recess, p, for receiving the curved part of this lever n. When this curved part of the lever n is in the recess p the inner end of the latch-pin Q is in one of the apertures o of the plate O. When the

lever *n* is drawn outward and turned to one side, so that its curved part rests against the side of the car and not in the recess *p*, the inner end of the latch-pin *Q* will be withdrawn 5 from the aperture *o* in the disk or plate *O*. The stem *R*, projecting from the rear end of the drawhead *A*, is surrounded by a spiral spring, *R'*, which serves as a buffer, and is held between two plates, *S* and *S'*, behind the draw-head, through which plates the stem *R* passes. The side edges of these plates *S S'* rest in wide vertical grooves *s* in the inner surface of the partitions *L*, thus permitting these plates to move vertically with the draw-head, and also 10 permitting the plates to be moved toward each other when the spring *R* is compressed. A buffer, *T*, is attached to the bottom of the end of the car, above the draw-head *A*. A triangular cam-plate, *V*, is attached to one side of 15 each draw-head, the lower edge of the cam-plate being beveled. These cam-plates are to move the link-guides *I* when the draw-heads come in contact.

The operation is as follows: When the cars 20 are uncoupled, and no link is held in the draw-heads, the pin *E* is lowered within the tube *D*, the spring *E'* is compressed, and the buffer-block *B* is pressed forward by its spring *B'* to such an extent that the tongue or plate *C* 25 covers the pin-aperture in the bottom of the draw-head and prevents the coupling-pin from being forced through the draw-head by its spring *E'* or by the action of the weights *H* on the outer ends of the levers *F*, which levers are 30 connected with the pin. If the coupling-link now enters, it pushes back the buffer-block *B*, so that the plate or tongue *C* clears the bottom aperture of the draw-head, thus permitting the spring *E'* or the weights on the levers 35 *F* to force the pin *E* upward through the openings in the draw-head and through the link *J*, which is thus coupled to the draw-head automatically.

If desired, the spring *E'* may be dispensed 40 with and the weights *H* used only, or, vice versa, the weights *H* may be dispensed with.

To guide the link *J* into the draw-head, the lever *I* is used, which can be lowered more or less, as circumstances may require. This lever 45 may be used to guide the link of the draw-head to which the lever is connected, or to guide the link of the opposite draw-head. The cam-plates *V* lower the link-guides *I* when the draw-heads come together, so that the link-guides will not interfere with the entering of the links. As circumstances may require, the draw-head *A* may have to be adjusted higher or lower, and to accomplish this the latch-pin *Q* is withdrawn from the aperture in the plate 50 or disk *O*, so that the same will be disengaged, and the crank *P* is turned, whereby all the shafts *M'* will be turned simultaneously, as they are all connected by the plate *N*. If the draw-head is in the position shown in Fig. 2 55 and the crank *P* is turned, the eccentric rollers *M* will lower the draw-head, and as soon

as the same has been lowered sufficiently the latch-pin *Q* is released, and is forced into one of the apertures *o* of the plate or disk *O*, and this locks the eccentric rollers *M* and the draw-head in the desired position. As stated, the vertical grooves *s* in the partitions *L* permit of a vertical adjustment of the plates *S S'*, the stem *R*, and the spiral spring *R'* with the draw-head. 70

These improved coupling attachments can easily be attached to any draw-head of the usual construction, and the coupling attachments can be used without devices for adjusting the draw-head vertically. 75

One of the levers *F* is provided with an upwardly-projecting arm, *W*, the upper end of which is directly below the outer end of the link-guiding lever *I*, above this lever *F*, so that when the lever *F* is raised to lower the 80 pin the inner end of the link-raising lever *I* will be lowered, so that this lever will not interfere with the coupling-link. 85

If desired, the coupling-pin may be arranged to work from above as well as from below. 90

Having thus fully described our invention, we claim as new and desire to secure by Letters Patent--

1. The combination, with the draw-head *A*, the shackling-pin *E*, and the pivoted lever *F*, 95 connected thereto, of the weight *H*, adjustable longitudinally upon the lever *F*, as shown and described.

2. The combination, with the draw-head *A*, tube *D*, coupling-pin *E*, and lever *F*, of the 100 slot *d* in the tube *D*, the pin *a* connecting the lever *F* and pin *E* through the slot *d*, as shown and described.

3. The combination, with the draw-head *A*, lever *I*, and link *E*, of the two prongs *i* on 105 said lever *I*, for guiding the link into the draw-head, as shown and described.

4. The combination, with the draw-head *A*, of the pivoted link guide-lever *I* and the cam-plate *V*, substantially as herein shown and 110 described, and for the purpose set forth.

5. The combination, with the draw-head *A*, of the partitions *L*, attached to the bottom of the car, between which partitions the draw-head is held, and of the eccentric rollers *M* between 115 the partitions, substantially as herein shown and described, and for the purpose set forth.

6. The combination, with the draw-head *A*, of the partitions *L* on the under side of the car, the eccentric rollers *M*, and devices for operating these rollers simultaneously, substantially as herein shown and described, and for the purpose of adjusting the draw-head vertically. 120

7. The combination, with the draw-head *A*, of the partitions *L*, the transverse shafts *M'*, 125 the eccentric rollers *M*, the cranks *m*, the plate *N*, and the crank-handle *P* at the end of one of the shafts *M'*, substantially as herein shown and described, and for the purpose set forth.

8. The combination, with the draw-head *A*, 130 of the partitions *L*, the shafts *M'*, the eccentric rollers *M*, the cranks *m*, the plate *N*, the disk

O, provided with apertures o and mounted on one of the shafts M', and the latch-pin Q, substantially as herein shown and described, and for the purpose of locking the draw-head in 5 the desired position.

9. The combination, with the draw-head A and partitions L, of the shafts M', the eccentric rollers M, the crank, m, the plate N, the disk O, mounted on one of the shafts M' and provided with apertures o, the latch-pin Q, the spring Q', and the bent locking-lever n, substantially as herein shown and described, and for the purpose set forth.

10. The combination, with the draw-head A and the partitions L, provided with wide vertical grooves in the inner surfaces of the plates

S S', the stem R, attached to the draw-head, and the spring R', surrounding the stem, substantially as herein shown and described, and for the purpose set forth.

11. The combination, with the lever F and the link-guiding lever I, of arm W, projecting upward from the lever F, for the purpose of operating the lever I with the lever F, substantially as herein shown and described.
